John H. Green,
By his Attorney
C. P. Jacobs.

UNITED STATES PATENT OFFICE.

JOHN H. GREEN, OF BLUFFTON, INDIANA, ASSIGNOR OF ONE-HALF TO
GEORGE F. MCFARREN, OF SAME PLACE.

BAG-TIE.

SPECIFICATION forming part of Letters Patent No. 466,301, dated December 29, 1891.

Application filed July 23, 1891. Serial No. 400,514. (No model.)

To all whom it may concern:

Be it known that I, JOHN H. GREEN, of Bluffton, county of Wells, and State of Indiana, have invented certain new and useful Im-
5 provements in Bag-Ties; and I do hereby de-
clare that the following is a full, clear, and
exact description thereof, reference being had
to the accompanying drawings, in which like
figures refer to like parts.

10 My invention relates to the construction of
devices for tying bags and sacks and will be
understood from the following description.

In the drawings, Figure 1 is a front view of
a sack filled with wheat with my device in
15 place. Fig. 2 is a similar view of a sack one-
half full fastened with my device. Fig. 3 is
a top view of my device locked. Fig. 4 is a
similar view unlocked. Fig. 5 is a front edge
view of the device when locked.

20 The tie is formed of a single piece of spring-
wire of any suitable material and is readily
made upon a former.

At 1 are one or more coils which form the
main spring.

25 2 is the arm that contains the male part of
the lock, and 3 the arm which is closed at the
end to receive the tang or hook 4 of the part
2. Beyond the locking ends are extensions 5
of the wires, forming compensating springs
30 terminating in tangs 6, which enter the bag
to prevent the tie from slipping up or down,
and when the parts are locked these exten-
sions 5 provide a second wire, which partly
encircles the bag, making the tie of double
35 strength at the points where there is likely
to be the most strain. It will also be seen that
there is pressure against the bag at the rear
end at the coil 1 and also at the locking ends 4
and at the points or tangs 6 of the extension.
40 This prevents the coil 1 from springing out and
allowing the device to unlock and spill the

grain. The bag, being encircled by the double
spring-wires and held at the rear and front
and by the hooks 6, makes a complete and per-
fectly secure device.

45

In order to prevent the loss of the tie, a
string may be passed through the coil 1 and
fastened to the bag in any suitable manner,
so that when the device is unlocked and hang-
ing down it will remain attached to the bag 50
convenient for use.

I am aware that ties have been formed of
wires bent in various shapes for securing bags;
but I am not aware that any device has been
constructed and arranged in the manner here-
55 in shown and described, and believe that it is
entirely new.

What I claim as my invention, and desire
to secure by Letters Patent, is the following:

1. A bag-tie formed of a single piece of 60
spring-wire having the coil 1 in the rear,
spring-arms 2 and 3 at the sides, a hook 4 for
engaging with the closed end of the wire on
the opposite side, and inner extensions 5, with
tangs 6 for entering the bag, substantially as 65
shown and described.

2. A tie for bags, composed of a single piece
of spring-wire having a coil 1 at one side, and
locking ends adapted to engage one with the
other for securing the same, the ends of the 70
wire extended inward to form a compensat-
ing spring and provided at their ends with
hooks for entering the bag to prevent the tie
from slipping, all combined substantially as
shown and described.

75

In witness whereof I have hereunto set my
hand this 16th day of July, 1891.

JOHN H. GREEN.
